UNITED STATES PATENT OFFICE.

DANIEL LONGWORTH, OF LONDON, ENGLAND.

POWER-HAMMER.

SPECIFICATION forming part of Letters Patent No. 498,354, dated May 30, 1893.

Application filed May 20, 1891. Serial No. 393,499. (No model.) Patented in England July 14, 1890, No. 10,963.

To all whom it may concern:

Be it known that I, DANIEL LONGWORTH, a subject of the Queen of Great Britain, residing at London, England, have invented new and useful Improvements in Power Hammers or Stamps, (patented in Great Britain, No. 10,963, dated July 14, 1890,) of which the following is a specification.

My invention relates to power hammers or stamps actuated by rotary shafts, and comprises improvements whereby such hammers or stamps are rendered more efficient than heretofore.

According to my invention the motion of the crank-shaft is communicated to the rod carrying the hammer (which rod is hereinafter referred to as the hammer-rod) through the medium of a lever pivoted on the frame of the machine, and connected at one end to the pin of the crank through the medium of a sliding sleeve and at the other by means of links to a cross-head sliding on the hammer-rod and carrying a cylinder which for convenience I will term a cushioning cylinder, within which is a piston secured to the hammer-rod, the said piston with the hammer-rod serving as guides for the said cushioning-cylinder. The pivot-pin or fulcrum upon which the lever oscillates or rocks is adapted to be placed in one or other of two or more sets of holes for adjusting the stroke of the hammer. For regulating the force of the blows delivered by the hammer, during the operation of the machine, a cylinder which I will term a controlling-cylinder is fixed to the framing and contains a piston connected to the hammer-rod. In the upper part of this controlling cylinder are holes or openings for permitting the free ingress and egress of air and in the lower part a valve or valves is or are arranged, which valve or valves admit air below the piston but prevent its escape. At one side of the controlling cylinder is a series of passages controlled by a valve in such a manner that all the said passages can be closed or one or more opened as required.

To enable my invention to be fully understood I will describe the same with reference to the accompanying drawings, which illustrate my improvements applied to a pneumatic hammer.

Figure 1 is a sectional front elevation, and Fig. 2 a section on the line α α Fig. 1 and Fig. 2^A a detail of a portion of Fig. 2, shaded. Fig. 3 is a sectional view illustrating a detail of construction. Fig. 4 is a view illustrating a modification.

a is the framing of the machine, and *b* is the crank-shaft supported in bearings in the framing and carrying belt pulleys *c*, *c'*, the belt running upon which is, as shown, designed to be shifted by the workman by means of the belt lever *d* and foot-lever *d'*, but which may be shifted by hand in the usual manner.

e is the lever pivoted in the framing upon the pin or fulcrum *f*, and *g* is the sleeve sliding upon the said lever at one end and connected to the pin *b'* of the crank.

h, *h* are the links connected to the other end of the lever *e* and to the cross-head *i* which fits and slides upon the rod *k* carrying the hammer *k'*, and *l* is the cushioning-cylinder, a collar *l'* on the neck of which engages at the sides under flanges *i'*, *i'* on the said cross-head, while the front and back are left free, as shown in Fig. 3, so that the lateral strain imparted to the cross-head when the links *h*, *h* are out of a vertical line will not be communicated to the cushioning-cylinder in such a manner as to increase the friction between it and the hammer-rod. The collar *l'* may be screwed upon the neck of the cushioning-cylinder *l* and furnished with a lock-nut *l*⁴, as shown in Fig. 4, to enable the said cylinder *l* to be adjusted vertically relatively to the position of the cross-head *i*.

m is the piston attached to the hammer-rod *k* and working in the cushioning-cylinder *l*.

In the cushioning-cylinder *l* are holes *l*², *l*² which serve to admit air above and below the piston *m* to form the usual elastic cushion when working, the said holes being placed in a recess, which, when necessary, is covered with fine wire-gauze *l*³ or other suitable material to filter the air.

From the foregoing description it will be understood that, when the lever *e* is rocked, a reciprocating up and down movement will be imparted to the hammer-rod *k* through the medium of the links *h*, *h*, the cross-head *i*, the cushioning-cylinder *l* and the piston *m*. As

the links h, h are very long relatively to the stroke of the rocking-lever e very little lateral strain is imparted to the cross-head i and, as the said cross-head is not rigidly connected 5 to the collar l' of the cushioning-cylinder, no lateral strain is imparted to the said cushioning-cylinder l . The latter therefore imparts no lateral pressure to the piston m or hammer-rod k , whereby packing and packing 10 glands for the hammer-rod k , and external guides for the body or neck of the cushioning-cylinder l can be dispensed with, the said cushioning-cylinder l being guided solely by the piston m and hammer-rod k . If the links 15 h, h are made so long relative to the stroke of the rocking-lever e that, practically, no lateral strain is imparted to the cross-head i , the latter can be secured directly to the neck of the cushioning-cylinder l .

20 n, n and n', n' are two sets of holes made in the framing a of the machine and corresponding holes are made in the rocking-lever e , these holes being in a line corresponding with the lowest position of the rocking lever. To alter 25 the stroke of the said rocking-lever the fulcrum-pin f is withdrawn from one set of holes and placed in another set, a pin o being placed in the holes p, p in the lever and frame to hold the rocking-lever e in position while the change 30 is being effected. The dotted lines q, q' indicate the range of movement of the rocking-lever when the pin is in the holes n, n , and n', n' respectively. Or, to be more explicit, the rocking lever e , being in its lowest position, that is to say, in the position shown in Fig. 2., the holes 35 n in the framing then correspond with one of the holes in the lever e ; and the holes n' in the framing correspond with the other hole in the lever e , while a third hole in the framing 40 corresponds with a hole p in the lever e ; that is to say, the three holes in the lever are all in line, and when the lever is in the position shown in Fig. 2., are opposite to corresponding holes in the framing. If now, it be 45 desired to shift the fulcrum pin f from the holes n into those shown in Fig. 2. and marked n' , the first operation is to take out from the fulcrum pin f , the pin o ; which normally prevents the said fulcrum pin from slipping 50 out of position. The said pin o , having been removed from the fulcrum pin, is introduced through the hole in the framing, into the hole p in the lever. The fulcrum pin f can now be withdrawn, the lever e , being prevented 55 from shifting owing to the fact that the pin o is passed through the framing into the hole p . The fulcrum pin f , having been removed from the hole n , can be introduced through the framing into the holes in the lever, to alter its length of throw.

60 r is the piston working in the controlling cylinder attached rigidly to the hammer-rod k , and s is the controlling cylinder attached to the framing a of the machine, the hammer-rod, as shown, passing through the said cylinder. This controlling cylinder has, at its lower end, a long bearing s' for the hammer-

rod k , which bearing s' may be furnished with a stuffing-box and packing gland when necessary. The upper end of the cylinder s 70 is in communication with the atmosphere through openings s^2, s^2 under the cover s^3 , and the lower end is provided with an air-inlet t having a valve t' . A series of air-inlet holes or openings t^2 is formed in the walls 75 of the cylinder s at a point a little below the piston r when the latter is at the top of the stroke, the said openings t^2 , with the opening t , serving to admit air under the piston during its upward stroke. The holes t^2 are not 80 furnished with valves and, when the stroke of the hammer is short, the inlet opening t and valve t' may be dispensed with, the inlet holes or openings t^2 alone being used to admit air under the piston r .

85 In a chamber or box u , forming part of or attached to the cylinder s and connected thereto by a series of passages u', u' at various heights from the bottom of the cylinder, is placed a slide-valve v . This slide-valve is shown as connected by means of rods and levers v', v^2, v^3, v^4 to a hand-lever v^5 under the control of the workman, but it may be connected, when required, to the foot-lever d' or to a separate foot-lever. The said 90 slide-valve is also shown as of the solid piston type, but any other type of slide-valve may be employed without departing from the nature of this invention. When the said slide-valve v is in its highest position it covers and closes the outer ends of all the holes or ports u', u' but, when in its lowest position, it uncovers the outlet of all the holes which are then free to communicate with the atmosphere through openings u^2, u^2 under 95 the cover of the box. When, during the upward stroke of the hammer, the piston r rises, air is drawn into the cylinder s below the said piston through the inlet opening t , and when the piston nears the top of its stroke, through the openings t^2 . When the piston r descends and passes the holes t^2 and closes the valve t' , the air is compressed between the said piston and the bottom of the cylinder forming an elastic resistance to the downward 100 motion of the hammer k' . When all the holes u', u' are closed by the valve v the maximum amount of compression and resistance to the downward motion of the hammer is obtained, so that the pallet or head w of 105 the hammer does not strike the block y on the anvil z . Should, however, all the holes u', u' be rapidly uncovered, the hammer would descend with all its force. A blow of intermediate force is obtained by uncovering a 110 greater or lesser number of holes, whereby the volume of air compressed in the cylinder is varied according to the blow required.

115 Although I have described my improvements as applied to hammers it is to be understood that they are equally applicable to stamps.

120 Having now particularly described and ascertained the nature of my said invention and

in what manner the same is to be performed, I declare that what I claim is—

1. In a power hammer or stamp, the combination with its frame, of the rocking lever *e*, links *h*, cross-head *i*, cushioning air-cylinder *l*, cylinder *s*, and hammer rod *k*, having the pistons *m* and *r*, the combination being and operating as set forth.

2. In a power hammer, or stamp, the combination with the frame, the hammer-rod and the power-actuating mechanism, of a piston working in the controlling cylinder, and an

air-cylinder *s*, having inlet openings *t*² and outlet ports *u' u'*, a slide valve for the same and an adjustable rocking lever *e*, pivoted on the frame and connected to and actuating the hammer rod, all substantially as shown and described.

DANIEL LONGWORTH.
